UNITED STATES PATENT OFFICE.

LAWRENCE M. PERSONS, OF CHICAGO, ILLINOIS, ASSIGNOR TO COOK ELECTRIC COMPANY, OF CHICAGO, ILLINOIS, A CORPORATION OF ILLINOIS.

PROCESS FOR MAKING HOLLOW RIVETS.

Original application filed October 20, 1920, Serial No. 418,306. Divided and this application filed May 23, 1923. Serial No. 640,823.

My invention relates to split tubular rivets and the process for making the same.

One object of my invention is the provision of a simple and efficient tubular rivet 5 capable of being easily expanded.

Another object of my invention is the provision of a tubular rivet internally threaded and capable of being expanded by adjusting a screw slightly larger than the internal 10 diameter of the rivet.

A further object is the provision of a tubular rivet formed of sheet material having the threads formed by stamping serrations in the sheet material before the latter 15 is made into tubular form.

A still further object is the provision of a simple and efficient method of making rivets, such as above referred to.

Other objects will appear hereinafter. 20 An embodiment of my invention is shown in the accompanying drawing, forming a part of this specification, and in which—

Fig. 1 is a perspective view of a blank from which my tubular rivet is formed;

25 Fig. 2 is a similar view of the blank having the serrations formed therein and the longitudinal edges bent up;

Fig. 3 is a similar view showing the tubular rivet completely formed;

30 Fig. 4 is an enlarged fragmental section of a motor core having a tubular rivet therein embodying my invention;

Fig. 5 is a fragmental section, more or less diagrammatically, illustrating the method of 35 forming my improved rivet; and

Fig. 6 is an elevation, more or less diagrammatical, illustrating the finishing process of making my improved rivet.

This is a division of application, Serial 40 No. 418,306, filed October 20, 1920.

My improved rivet has the advantage that it can be made very economically, much more so than where the tubular rivet must be made from a tube and internally threaded with 45 dies.

In forming my rivet I first cut out a blank, such as indicated in Fig. 1, of the desired size to give a finished rivet in the size to be made. The next step in forming 50 the rivet is to place it in the position indicated in Fig. 5 at 7 in a forming die 8. The punch 9 is then brought down onto the blank 7 pressing it from its dotted line position to its full line position shown in Fig.

55 The punch 9 and die 8 are so formed that the serrations 10, clearly indicated in Fig. 2, will be formed. At the same time the die 8 and punch 9 will turn up the longitudinal edges 11 of the blank, as indicated in Fig. 2. The blank is next placed 60 in a die, such as indicated in Fig. 6, and upon members 12 of such dies being forced in the directions of the arrows 13 the blank will be bent from its full line position to that indicated in dotted lines in said Fig. 6, thus completing the formation of the split 65 tubular rivet with its internal threads.

This rivet will be useful in many places and I find it particularly adaptable for securing the laminations of motors, dynamos, 70 and the like, together. In Fig. 4 I have indicated the usual core laminations 14 of a motor which are provided with registering perforations 15 therein for receiving a rivet to secure such laminations together. With 75 the use of my improved rivet the latter is placed in the perforations 15 and its ends riveted in the usual manner. After the rivet has been riveted screws 16 are passed through the cover members 17 of the usual motor, or the like, constructions and threaded into the serrations 10 of my improved rivet. In forming the serrations 10 it will be understood they are to be made 80 so that when finished the screw threads 85 formed thereby will have the same pitch as the screws 16 to be used.

I preferably use screws 16 slightly larger than the internal diameter of the split rivets so that in forcing the screws into said rivets the latter will be expanded into close 90 contact with the walls of perforations 15. The rough edges 18 of the rivet will also tend to cut into the walls of the perforations 15 and facilitate holding the rivet against 95 rotation while the screws 16 are being adjusted into or out of position.

In Fig. 4 I have indicated a screw 16 in each end of one of my improved rivets. This expands both ends of the rivet and binds all of the laminations together. One of the screws 16 holds the laminations 14 up against a shoulder 19 in the casing 20, and the other screw 16 holds the cap 17 in place on the frame. These parts may be arranged in other manners, an essential 100 thing being that the screws extend into the rivet.

I claim:—

1. The method of forming tubular rivets comprising the step of stamping shallow serrations in one side only of a piece of sheet material and then bending the sheet material into a continuous arc to produce a tubular form with the serrations providing internal screw threads of a depth less than that of the thickness of the material.
- 10 2. The method of forming an expandible tubular rivet comprising the step of stamping shallow serrations in one side only of a rectangular piece of sheet material, folding the piece of sheet material to produce a tubular form with the said serrations providing internal threads of a depth less than that of the thickness of the material.
- 15 3. The method of forming a tubular rivet comprising stamping transverse serrations in a piece of sheet material and at the same time turning up the longitudinal edges of such sheet material and thereafter bending said sheet into tubular form so that the ser-

rations provide internal threads for the completed tubular rivet.

25

4. The method of forming a tubular rivet comprising cutting out a blank of sheet material of proper form then forming transverse serrations in one side only of the sheet material and finally exerting pressure on said sheet from opposite edges thereof to bend the sheet material into tubular form so that the serrations form screw threads.

30

5. The method of forming a tubular rivet comprising the steps of stamping serrations in one face of a piece of sheet metal and at the same time bending the edges of said piece and thereafter exerting pressure on said bent edges to bend said piece into cylindrical formation with the serrations at the interior thereof.

35

In testimony whereof I have signed my name to this specification on this 15th day of May, A. D. 1928.

LAWRENCE M. PERSONS.
